GASOLINE SAFETY CAN

Charles S. Packer, Chicago, Ill., assignor to Just-
rite Manufacturing Company, Chicago, Ill., a
corporation of Illinois

Application December 9, 1940, Serial No. 369,191

1 Claim. (Cl. 221—15)

The invention relates to containers for liquids and has more particular reference to a gasoline container of the portable type having improved safety features eliminating the danger of fire or explosion of the gasoline.

A principal object of the invention is to provide a safety gasoline can in which the liquid can be transported or stored with the minimum of danger, which will have special capping means for closing the pouring spout and keeping the same closed unless positively opened by the attendant, and which will also embody an improved vent in connection with said spout to facilitate pouring.

In the container of the invention the spout is provided with a protective screen extending downwardly into the container through which the liquid may flow to the spout for pouring but which will effectively prevent a flame from contacting the gasoline within the can. In the event the gasoline within the spout should be ignited during pouring the fire would thus be confined within the cylindrical screen.

Another object is to provide a vent or by-pass for said discharge spout which will admit the required amount of air within the container during pouring, thus releasing the gasoline in a uniform flow and preventing turbulence of the liquid within the spout during said operation.

With these and various objects in view, the invention may consist of certain novel features of construction and operation, as will be more fully described and particularly pointed out in the specification, drawings and claim appended here-to.

In the drawings, which illustrate an embodiment of the device and wherein like reference characters are used to designate like parts—

Figure 1 is an elevational view, parts being shown in section, of a container for gasoline or other volatile liquid having the improvements of the invention applied thereto;

Figure 2 is an elevational view of the top portion of the container with parts being shown in section and with the cap member in open position for pouring;

Figure 3 is a modified arrangement of handle and operating means for the cap member;

Figure 4 is a top plan view of the container shown in Figures 1 and 2;

Figure 5 is an elevational view from the rear of the handle showing the structure of the handle and the connection of the operating means thereto; and

Figure 6 is an elevational view showing in de-

tail the releasable link for connecting the handle with the cap member.

Referring to the drawings, the can or container 10 is of conventional construction having a pouring or discharge spout 11 and a reinforcing top plate 12. The spout is tubular, being suitably secured to the can 10 to form an opening to the interior and supporting within the can a cylindrical wire mesh screen 14 having a wire mesh bottom. The spout is provided with a cap 15 having a hinge portion which is hinged at 17 so that the cap may oscillate from a closed position, as shown in Figure 1, to an open position, as shown in Figure 2. The stud 17 hinging the cap 15 is journaled in ears 18 formed in spaced relation on the solid portion 20 of the spout.

Since the present container is adapted for gasoline or other volatile liquids the cap is resiliently maintained in closed position on the spout by a wire spring 21 which passes around the hinging stud 17 and then around the portion 22 on the cap, thereby exerting a pressure on the cap to hold the same closed. The bail or handle 23 for carrying the container and for opening the cap to permit pouring is pivoted at 24 to spaced ears 25 formed integral with the top plate 12. A wire spring 26, having connection with the pivot stud 24 and anchored at one end on the top plate and at its other end on the handle, functions to maintain the handle in forward position toward the cap.

Movement of the handle is transmitted to the cap by a link 27, Figures 2 and 6, pivoted to the cap at 28 and having connection with the handle 35 through the pin 30 passing through the slot 31 in the link. The handle is constructed as shown in Figure 5, with bifurcated lower extremities 32 within which the link is located. The pin 30 is held by both extremities and by passing through the slot the handle has limited free movement which is not imparted to the cap. Further movement beyond this limit is imparted to the cap as evident by referring to Figure 2, and accordingly, the spout is opened. The same 40 may be held open as long as the handle is held in the down position by the operator. Release of the handle will return the same to upright position and some distance beyond, under tension of spring 26. The spring 21 returns the cap to 45 closing position on the spout.

In accordance with the invention the link 27 is provided with an opening 33 to the slot 31, whereby the link is releasable with respect to handle 23. The pin 30 will be positively retained 50 within the slot 31 only after said pin has passed

beyond the opening 33. For opening the cap member it is therefore necessary as the operator starts to move the handle 23 in a direction away from the cap, Figure 1, to also move the link by gripping and lifting the rear flattened end 34 of the link. This action on the link maintains pin 30 within the slot 31 and as movement of the handle continues the pin will presently pass beyond opening 33, whereupon the operator may then discontinue the lifting action imparted to the link. If the handle 23 is moved rearwardly and link 27 is not lifted, as above described, the pin 30 will pass out of the slot through opening 33, the action taking place naturally since opening 33 has been located with respect to the arcuate path of movement of pin 30 for this purpose.

The invention therefore provides a handle or bail which may be described as being normally released or at least releasable from the link 27 which provides the connecting means between the handle and the cap member. However, the link may be easily connected to the handle when it is desired to open the cap member by merely lifting the rear end of the link as initial movement in a rearward direction is imparted to the handle. This structure provides a safety measure since a positive act of the operator is required to connect the cap member to the handle so that when the handle is moved rearwardly the cap member will be opened.

In the modification as shown in Figure 3 the pouring spout 11 is provided with a cap 115 pivoted at 117 so as to have movement against the tension of the wire spring 121 from a closed position to an open position, as shown in dotted lines in said figure, to permit pouring of the contents of the container. The modification resides in a change in the form of handle to facilitate actuation of the cap to cause opening of the same. The stationary part of the handle 135 is in the form of a substantially rectangular frame, being suitably secured along the bottom side thereof to the reinforcing cap 112. The movable portion of the handle 136 has location within part 135 and is rigidly secured at 137 to the link 127, which link corresponds in all respects to the part 27 of the handle mechanism shown in Figures 1, 2, 4 and 5, the said link having pivotal securing at 128 to ears 118 formed integral with the solid portion of the spout.

In operation of the handle as shown in Figure 3 the hand of the operator is placed against part 135 and the fingers of said hand are located forwardly to grasp part 135. The said movable part 136 may therefore be drawn rearwardly toward the operator by closing the hand, which movement of said part is transmitted to link 127, causing the pivoted cap 115 to oscillate into an open position against the tension of spring 121. When the operator releases his hand from portion 135 and 136 the cap will automatically close since the spring 121 yieldingly forces the cap into said closed position on the spout 111.

The invention contemplates the provision of a vent or by-pass for the pouring spout which will admit the required amount of air within the container during the pouring operation. Said vent is applied to both forms of the invention and is shown in both Figures 1 and 3. The solid portion 20 of the pouring spout is provided with a passage 40 extending diagonally downward toward the interior of the container and having connection at its lower end with a tube 41. The tube 41 forms a continuation of passage 40 and said tube extends rearwardly within the con-

tainer so that the enlarged rear end portion 42 of the same would be located adjacent the top of the container and approximately diagonally opposite the pouring spout 11. A screen 43 may be located over the opening of portion 42 and in this manner a fire preventive screen is provided, preventing flame which may exist in the pouring spout from travelling back through tube 41 and entering the interior of the container.

10 The passage 40 terminates within the pouring spout adjacent the upper end thereof and since the same is located in the rear wall the vent does not interfere with the pouring operation. On the other hand, during pouring of the gasoline or other liquid from the container the vent will operate to conduct air to within the container, thereby relieving the reduced pressure which would otherwise exist as a result of the pouring operation. The gasoline or other liquid will flow from the container in a uniform manner and all turbulence of the liquid within the pouring spout is eliminated.

15 It will be observed from the foregoing that the invention provides a safety gasoline can in that the spout is automatically closed by the cap member upon release of the handle and even during pouring when the spout is open provision is made by means of the wire screen to prevent a flame from passing into the interior of the can. The 20 wire screen functions to permit flow of the liquid through the screen to the spout and prevents in a manner which is well known the passage of a flame through the screen. Thus, even though the gasoline or other volatile liquid in this pouring 25 spout should become ignited during pouring the flame will not be able to ignite the body of liquid within the container and furthermore said flame could easily be extinguished by closing the cap member as this would shut off all access to the air.

30 The by-pass or vent conducts air from the spout to the interior of the container, preferably in the upper portion thereof diametrically opposite the spout, which portion of the container 35 will be void of liquid in all cases by reason of the angle of the container during pouring. The admission of air to the container will facilitate pouring since the flow will be uniform and all turbulence of the liquid will be eliminated. The 40 vent is operative during pouring since when the cap is closed the vent is shut off from the atmosphere. As a further safety measure a fire preventive screen may be fixed to the rear opening of the vent formed by the tube 41, which is in effect a continuation of the passage 40 in the discharge spout.

45 The invention is not to be limited to or by details of construction of the particular embodiment thereof illustrated by the drawings, as various other forms of the device will of course be apparent to those skilled in the art without departing from the spirit of the invention or the scope of the claim.

50 What is claimed is:

55 In a container having a discharge spout, a closure member pivotally associated therewith and having a closed and an open position with respect to the spout, a carrying handle for the container pivotally associated with the top wall of the container substantially centrally thereof so as to have a forward and a rearward position when located toward and away from the spout respectively, a link connected at one end to the closure member and having a longitudinal slot

in its other end portion, a pin on the handle adapted for location within said slot whereby to operatively connect the handle and closure member, said link having an opening to the slot at the end adjacent the closure, said pin having movement in an arc upon pivoting of the handle to and from its extreme forward position to cause the pin to alternately enter and leave said slot

5 through the opening, whereby the link must be manipulated to operatively retain the pin within the slot upon initial movement of the handle from its said forward position, and said link having a flattened rear portion for facilitating said manipulation.

CHARLES S. PACKER.
